[57] ABSTRACT

A cylindrical drum is mounted for rotation about a vertical axis within a housing. A driven rotor is coaxially mounted within the drum. A fluid containing solid particles is introduced into the rotating rotor which throws the fluid toward the drum, causing rotation of the drum. As the drum rotates the particles collect on the drum side wall. An inwardly extending annular baffle prevents fluid from escaping from the bottom of the drum during normal operation, and clarified fluid is discharged through ports in the top cover of the drum. To purge the drum of accumulated particles, the drum is braked while the rotor continues to rotate. There is substantial clearance between the rotor and the drum. With the drum braked, the rotor creates a washing or eroding action in the fluid which breaks the particles free from the drum side wall, allowing them to be resuspended in the fluid. Fluid with resuspended particles flows over the baffle and out the bottom of the drum.

SELF-PURGING CENTRIFUGE

BACKGROUND OF THE INVENTION

The invention pertains to self-purging centrifuges and in particular to a centrifuge wherein the purging involves the setting up of a washing or eroding action.

A known way of purging a centrifuge involves scraping or plowing the accumulated solid particles. This method is shown in U.S. Pat. No. 3,403,848 (Windsor et al.). In Windsor there is substantially no clearance between the rotor blades and the side wall of the bowl. When the rotor is braked it merely scrapes the accumulated particles from the side of the bowl and they drop through an annular baffle which is raised toward an opening in the bottom of the bowl.

There are some problems associated with the Windsor apparatus. If fluids with dense solid particles are being centrifuged the rotor may become firmly embedded in the accumulated particles so that when the rotor is braked, the braking force is also transmitted to the bowl, and scraping action does not occur. Furthermore, apparatus using the scraping method in purging must be designed to withstand relatively large shock forces. In the present invention, the forces set up during purging are relatively small, yet hard packed, as well as soft, solid particles are completely purged.

SUMMARY OF THE INVENTION

The invention is a self-purging centrifuge including a drum and a rotor assembly. The drum has a side wall and a top wall member and is mounted for rotation about a generally vertical axis. The rotor assembly is coaxially mounted within the drum for independent rotation. The rotor assembly includes a plurality of vanes, the outer edges of which are spaced a substantial distance from the side wall of the drum. Contaminated fluid which is to be centrifuged is introduced into the rotor assembly. The contaminated fluid contains solid particles which are to be separated from the fluid. A driving means rotates the rotor assembly at a predetermined rate. The rotating rotor assembly throws the contaminated fluid outwardly toward the side wall of the drum. The rotor assembly imparts a rotating movement to the contaminated fluid directly toward the side wall of the drum, which causes the drum in turn to rotate. As contaminated fluid is introduced into the rotor assembly and directed toward the side wall of the drum, an annular wall of fluid is built up along the side wall of the drum. Centrifugal forces cause the particles to accumulate along the side wall of the drum. The inner portion of the wall of fluid is clarified because the solid particles are forced outwardly. The clarified fluid is discharged through openings in a top wall member of the drum. The openings are spaced from the side wall of the drum and the blades of the rotor assembly extend beyond the openings. An annular baffle extends inwardly from the bottom of the side wall of the drum. The inner edge of the baffle is spaced from the side wall of the drum a greater distance than the outermost area of the openings in the top wall member of the drum so that liquid escapes out the openings rather than over the edge of the baffle. Particles are collected in the area on the side wall of the drum between the top wall member of the drum and the baffle on the bottom of the side wall of the drum. Braking means abruptly slows or stops the rotation of the drum to initiate a purge cycle.

In the purge cycle the rotating fluid wall is disrupted and the accumulated particles are resuspended in the fluid. The purge cycle is ended as the fluid with the particles resuspended drains over the baffle and out of the lower portion of the drum.

The clarified fluid is collected in an annular chamber in a housing which surrounds the drum and the rotor assembly. The ring of openings in the top wall member of the drum, through which the clarified fluid is discharged from the drum, are covered with a ring having louvers formed therein. The louvered ring prevents the discharge of fluid from the drum during the purge cycle. The louvered ring is mounted over the inside of the openings. A shield in the form of a ring is mounted adjacent the outside of the openings to prevent splashing. The annular baffle is a rim-like member and can be removed from the side wall of the drum and replaced with another baffle with a different cross section and inner diameter. The cross section of the baffle is generally triangular.

Because there is substantial clearance between the blades of the rotor assembly and the side wall of the drum a washing or eroding action can be set up in the wall of fluid established in the drum. When the drum is braked, the washing action causes the accumulated particles to be resuspended in the fluid. Circulatory flow patterns are set up in the fluid causing the particles to become resuspended. The circulatory flow patterns promote drainage of the fluid.

BRIEF DESCRIPTION OF THE DRAWINGS

FIG. 1 is an elevational view of the centrifuge, portions thereof being broken away and shown in section;

FIG. 2 is a sectional view of FIG. 1 as taken generally from the irregular line 2-2 of FIG. 1;

FIG. 3 is a sectional view as seen from the line 3-3 of FIG. 1 showing the bottom area of the drum from which the purged fluid is discharged; and

FIG. 4 is a sectional view as seen from the line 4-4 of FIG. 1 showing the rotor assembly vanes and the top wall member of the drum.

DESCRIPTION OF THE PREFERRED EMBODIMENT

Referring to FIG. 1, the centrifuge has a drum including a cylindrical side wall 10, a top wall member 12 and a frustoconical bottom member 14. The periphery of wall 14 is attached to the bottom edge of side wall 10 and the center extends into the drum. The rotor assembly includes a shaft 16, a fin assembly 18 bolted to shaft 16, and a set of flat, plate-like vanes 20 bolted to the fin assembly 18. In the embodiment shown, vane set 20 includes four vanes spaced 90 degrees apart. The drum and the rotor assembly are mounted in a housing including a generally cylindrical body 22, a top cover 24, and a bottom portion 26. The drum and the rotor assembly are concentrically mounted and rotate independently about a vertical axis. The drum rotates on bearings 28 and 30 mounted in cover 24 and bottom member 14, respectively, and the rotor assembly rotates in bearings 32 and 34 mounted in wall member 12 and bottom portion 26, respectively. A motor (not shown) drives the rotor assembly through a set of belts 36 and a pulley 38 mounted on shaft 16.

Contaminated fluid, that is, fluid containing solid particles, enters the centrifuge through a feed pipe 40 and is introduced into the rotating assembly. The con-

taminated fluid, which for example may be machine tool coolant carrying metal chips or the like, is thrown or directed outwardly by the rotating fin assembly 18 and vanes 20 toward side wall 10 of the drum. The drum is driven by the viscous or shear forces associated with the fluid that is directed outwardly and rotated by the fin assembly 18 and vanes 20. In steady state operation the rotational rate of the drum lags behind that of the rotor assembly by 50 to 300 rpm. Typically the rotor assembly is driven at about 3,000 rpm. As the drum and rotor assembly rotate a wall of fluid is built up on side wall 10 of the drum. Centrifugal forces cause the particles in the fluid to be thrown radially outwardly to accumulate in the portion of the fluid wall along side wall 10 of the drum.

As the wall of fluid builds up, clarified fluid is discharged through a set of equally spaced openings or ports 42 formed in a circle concentric with shaft 16 in top cover 12 of the drum, and is collected in an annular chamber 44 within the housing which surrounds the drum. The outer wall of chamber 44 is formed by body 22 of the housing and the inner and bottom walls are formed by wall members 46 and 48, respectively. A ring 50 having louvered openings therein is placed over the inside of ports 42 to prevent escape of contaminated fluid through the openings 42 during the purge cycle. A ring-like baffle or shield 52 is placed over the outside of the openings 42 to prevent splashing as the clarified fluid is being discharged. Baffle 52 is spaced above the openings 42 and is secured to top wall member 12 at its inner edge to provide an unobstructed discharge space facing outwardly toward a curved splash cone 54 which directs the outwardly thrown fluid downwardly into chamber 44.

An air brake 56 is used to slow and stop the drum when the purge cycle is initiated. When brake 56 is actuated, a shoe 58 is driven upward and held against a projection 60. Projection 60 is in effect an extension of the drum.

An annular rim or baffle 62 having a generally triangular cross section is secured to the bottom of the drum side wall 10 with one side wall thereof attached to the drum side wall and an opposite apex thereof forming a circular edge or lip 64 over which the fluid and resuspended particles flow during the purge cycle. The inner edge or lip 64 of baffle 62 extends inwardly beyond the centers of ports 42. Note also that the outer edges of vanes 20 extend beyond the outermost edges of ports 42. Particles are accumulated on the side wall 10 between the upper cover 12 and the baffle 62.

When the drum is stopped or slowed the rotating vanes 20 disrupt the fluid, and the accumulated particles are resuspended in the fluid. As the purge cycle continues, the fluid and the resuspended particles flow inwardly and downwardly along the upper surface 72 of rim or baffle 62, downwardly over lip 64, outwardly through openings in side wall 10, downwardly through a series of circumferentially spaced openings 27 in bottom portion 26 and finally through an outlet 66 formed in a lower wall 23 of housing 22.

Referring to FIG. 3 the posts are referenced with numeral 68. Posts 68 are formed such that the sides of the posts are substantially aligned with the flow of the fluid as it is discharged from the bottom of the drum during the purge cycle. Thus posts 68 do not impede the outward flow which circulates around the inner surface of

body 22. This prevents the fluid that is discharged during purging from reaching bearings 30 and 34.

An access opening 69 is formed in side wall 22 radially outwardly of the discharge openings of drum 10. The opening 69 provides a convenient means to gain access to screws which mount the baffle 62. Thus, the baffle 62 may be removed and replaced without complete disassembly of the centrifuge. The opening 69 also forms a convenient means to clear or dislodge solids which may accumulate in the area adjacent the base of the rotor assembly.

As shown in FIG. 4 the louvered ring 50 prevents the flow of fluid through ports 42 during the purge cycle. Assuming that the rotor assembly and the fluid is moving to the right the fluid would have to double back to the left before it could flow up and out ports 42. I have found that this does not occur.

As shown in FIG. 2, clarified fluid collected in chamber 44 is removed from the centrifuge through an outlet pipe 70.

The purging of solids is accomplished partly by utilizing the instability of the boundary layer created at the inner surface of side wall 10 when the drum is slowed or stopped by the brake. A rotating flow is unstable if the magnitude of VR decreases with R , where VR equals the product of tangential velocity (V) and radius (R).

Where VR decreases with increasing R the centrifugal force acting upon an increment of fluid near the axis of rotation is greater than the force acting on an increment of fluid at a larger radius. Therefore, fluid near the axis tends to move outwardly toward the drum side wall 10 to a greater extent than the fluid that is near side wall 10. As the inner fluid moves outwardly the outer fluid near the side wall 10 is displaced.

The conditions for unstable rotating flow always exist at the boundary layer between a rotating flow (i.e., body of fluid) and the wall of a static container (braked drum). Fluid in the boundary layer, slowed by the frictional drag of the drum wall, tends to be displaced radially inward by the faster moving body of fluid nearer the axis of rotation. This interchange of fluid is greatly aided by the presence of a radial surface since the boundary layer at the radial surface is also unstable and provides a path for fluid at the wall to travel inward. This radial surface is shown as downwardly and inwardly sloping surface 72 of baffle 62 in FIG. 1. In the preferred embodiment, surface 72 is slanted downward but this is not necessary and surface 72 may be relatively level, i.e., horizontal.

In the purge cycle the drum is stopped, but the rotor assembly continues to be driven. The increased turbulence set up in the fluid near vanes 20 resuspends the particles accumulated along the wall and promotes drainage by a secondary flow phenomenon.

Although not necessary, the incoming flow of contaminated fluid is generally shut off or reduced during the purge cycle. The purge cycle may be initiated either at periodic intervals or by a sensor. In any case purging takes place before the accumulated particles reach the vanes 20 so that a significant quantity of fluid remains in the drum for erosion and resuspension of the particles, and the vanes are not embedded in the accumulated particles thus restricting or preventing the relative motion of the drum and rotor assembly which is necessary for proper purging.

As drum rotation is stopped, two separate equally important actions of the purge cycle begin. The first is the washing or erosion and resuspension of accumulated particles. This is accomplished by the washing action caused by the rotational speed of the rotor assembly within the drum as the drum is being braked. Once the particles are loosened they are resuspended in the rapidly moving fluid.

The second action, occurring simultaneously with the first, is the drainage of the particle-laden fluid due to the secondary flow pattern created by the braking of the drum. A slow moving boundary layer is created adjacent side wall 10. The faster moving fluid of the inner portion of the wall of fluid tends to displace the boundary layer fluid. The radial surface 72 provided by the baffle 62 at the bottom of the drum provides a means for the exchange of fluid to take place. Slow moving boundary layer fluid flows down and inward along surface 72. The faster moving fluid, displacing the boundary layer fluid, is itself slowed by side wall 10. The profile of the wall of fluid within the drum becomes thicker at the bottom because of the downward boundary layer flow, and becomes thinner opposite the rotating vanes which maintain high rotation of the fluid. A circulatory flow pattern is set up, with slow moving fluid from the thick lower portion experiencing a low centrifugal force, flowing upward along the inner surface of the fluid wall to take the place of the faster, outwardly moving fluid, experiencing high centrifugal forces, which has displaced the boundary layer fluid. The opening in the bottom of the drum formed by baffle 62 is sized to allow a controlled rate of fluid flow out of the drum with this circulatory flow pattern as described. As some fluid flows out, the effect of the vanes decreases, allowing fluid to flow out faster until all of the fluid "slides" out the bottom opening.

The above discussion of the action of the fluid wall at the bottom of the drum is also true to a lesser extent at the top of the drum where the drum cover 12 provides a radial surface for the boundary flow. The phenomenon at the top is not as effective because of the close proximity of vanes 20. When thickening of the fluid wall occurs at drum cover 12, fluid extends inside of ports 42 and contaminated fluid can over flow into the "clean" section of the centrifuge. To prevent this, louvers 50 are placed over each of the ports 42. The louver openings are aimed so that, with the drum stopped, the fluid, which is rotating at a high velocity, must double back in order to flow out through ports 42. Therefore at the high relative speed involved during purge, fluid is unable to exit through the ports 42. During normal operation, the speed of the rotor, drum and fluid is about the same so as not to interfere with the discharge of clarified fluid through ports 42. As shown, the louvers 50 are formed as part of an annular ring. However, each louver 50 may be formed from a separate piece of material and mounted to the inside of top cover 12.

An important variable effecting the purging of solids is the fluid discharge time, that is, the time it takes for the drum to be emptied of fluid when the brake is actuated and the input flow of contaminated fluid is shut off. Fluid discharge time can vary from three or four seconds upward and is influenced most by the inner diameter of baffle 62 and the viscosity of the fluid. The boundary layer created when the drum is stopped

causes a thickening of the fluid wall at the bottom of the drum.

If the inner diameter of baffle 62 is too small, fluid will not drain from the drum but will continue to recirculate within the drum under the influence of the vanes 20. If the thickening portion of the fluid extends inward of the edge 64 of baffle 62, fluid will begin to drain from the drum at a rate determined by the size of the drum opening and the fluid profile.

For a given rotor assembly speed and centrifuge design, the fluid profile is determined most by viscosity and to a lesser extent by the depth that vanes 20 extend into the wall of fluid. During the discharge period of the purge cycle, previously accumulated particles are being eroded by the shear forces imposed by the rapidly rotating fluid. If the discharge period is very brief, for example three to five seconds, not all of the caked particles will be resuspended and therefore the particles will not be completely purged from the drum. Obviously if little or no liquid is discharged, that is if the discharge period is infinite, particles will not be purged even though suspended.

It has been found that a discharge time between 10 and 15 seconds is the most practical. The inner diameter of baffle 62 becomes critical above this range so that fluid may not discharge at all because of slight decreases in viscosity due to temperature rise. For a purge time of less than about 10 seconds, particles may not be completely resuspended. Dependent upon the range of fluid, viscosities that are encountered by the self-purging centrifuge, the inner diameter of baffle 62 may need to be sized for the particular application. Two or three baffles with different inner diameters may be sufficient to cover a range. Some extension of the effective discharge time is possible by permitting input flow of contaminated fluid to continue for a few seconds after the drum has been stopped. The depth the vanes penetrate into the wall of fluid has an additional effect on discharge time and erosion forces. However, benefits gained from increasing the depth of vanes 20 into the fluid beyond about one-quarter inch do not appear commensurate with the greater forces and loads on the drive motor and belt, etc. Adjustable vanes may be appropriate and at any rate the vanes must be replaced periodically because they are subject to erosion during the purge cycle.

The quantity of particles affects the ability to purge in two ways. First, with a large accumulation of particles there are more particles to be eroded and suspended. Secondly, as the quantity of particles increases, the quantity of fluid available for erosion and resuspension of the particles decreases. In tests of a model of the embodiment of the invention described above, the limit of what can be purged effectively appears to be about 100 cubic inches of particles (approximately one-third of the fluid volume) for the contaminants tested. This limit is variable and depends upon the type of contaminant. In the embodiment tested the fluid capacity of the drum is about 5 quarts.

Ideally the purge cycle is initiated whenever the accumulation of particles reaches the maximum amount that can be reliably purged. This results in the least amount of fluid passing through the drag-out or settling tank, the least wear and tear on the apparatus, and the least down-time for the centrifuge, i.e., time when it is not centrifuging and clarifying fluid.

The time it takes to accumulate the proper amount of particles depends on the generation rate. In many applications where there is not an extreme variation in particle generation rate, the purge cycle can be initiated on a timed-interval basis. This interval can be set based on an estimate of the particle generation rate of the system and then adjusted through experience. This kind of control can be accomplished by a reset timer (adjustable in the range of 5 minutes to several hours) activating a program timer which controls the sequence of events during a purge cycle of about 15 to 30 seconds.

The sequence of events during the purge cycle can vary. The basic pattern is for the brake to be activated and the feed pump to be shut off at the beginning of the purge cycle and for the brake to be released and the pump turned on again after a delay of about 15 seconds. This method is satisfactory in most instances. In some cases, however, where the particles are difficult to purge, the sequence of events can be changed. For example the feed pump can be allowed to run for a few seconds after the drum has been braked. This extends the time during which particles are being eroded or washed and provides additional fluid for resuspension of the eroded particles. Alternatively the fluid flow during the purge cycle may be reduced rather than shut off completely. In this way the purge cycle can be extended indefinitely.

What is claimed is:

1. A self-purging centrifuge, comprising:
  - a drum having a side wall and a top wall member, mounted for rotation about a generally vertical axis;
  - a rotor assembly coaxially mounted in said drum for independent rotation with respect to said drum, said rotor assembly comprising a plurality of vanes having the outer edges thereof spaced a substantial distance from said side wall of said drum;
  - means for introducing a fluid containing solid particles to be separated therefrom, into said rotor assembly;
  - means for driving said rotor assembly at a predetermined rotational speed to throw the fluid and solid particles outwardly toward said drum side wall, said fluid rotating therewith, and said rotating fluid in turn causing rotation of said drum;
  - said top wall having openings therein for discharging clarified fluid, said openings each having an outer edge spaced from said side wall;
  - an annular baffle extending inwardly from the bottom of said drum side wall, to define with said top wall, said side wall and said outer edges of said vanes a particle collection area therebetween, said baffle having an inner edge spaced from said side wall a greater distance than the outermost edges of said openings in said top wall; and
  - means for abruptly slowing the rotation of said drum, to initiate a purge cycle by disrupting the rotating fluid and thereby resuspending the separated particles in the fluid, said liquid and resuspended particles draining from said drum over said baffle during the purge cycle.

2. The apparatus of claim 1 wherein said openings in said top wall are arranged in a circle formed about said axis.

3. The apparatus of claim 2 wherein said rotor assembly comprises a plurality of radially extending flat vanes

each having a vertical outer edge thereof terminating between said openings in said top wall and said side wall.

4. The apparatus of claim 3 wherein said outer edges of said vanes are positioned closer to said openings than to said side wall to thereby provide an open annular collection area of substantial depth between said vanes and said side wall.

5. The apparatus of claim 1 including louver means mounted inside said top wall member and over said openings, said louver means having louver openings aimed in the direction of fluid rotation, said louver means thereby blocking passage of fluid and resuspended particles through the openings during the purge cycle while permitting flow through said louver openings during normal operation.

6. The apparatus of claim 1 wherein said baffle is a rim-like member removably secured to said drum side wall.

7. A self-purging centrifuge, comprising:

- a housing having a vertical axis;
- a drum having a cylindrical side wall, and top and bottom wall members, mounted for rotation in said housing about said axis;
- a rotor assembly coaxially mounted in said drum for independent rotation with respect to said drum, said rotor assembly comprising a plurality of radially extending flat vanes each having a vertical outer edge thereof spaced a substantial distance from said side wall of said drum to define a particle collection area therebetween;
- means for introducing a fluid containing solid particles to be separated therefrom, into said rotor assembly;
- means for driving said rotor assembly at a predetermined rotational speed to throw the fluid and solid particles outwardly toward said drum side wall, said fluid rotating therewith, and said rotating fluid in turn causing rotation of said drum;
- said top wall having openings therein, spaced from said side wall, for discharging clarified fluid, said drum side wall collecting the solid particles being centrifugally removed therefrom;
- an annular rim extending inwardly from said drum side wall and adjacent said bottom wall, to further define with said top walls said particle collection area therebetween, said rim having an inner lip spaced from said side wall a greater distance than said openings in said top wall;
- means for abruptly slowing the rotation of said drum to initiate a purge cycle by disrupting the rotating fluid and thereby resuspending the separated particles in the fluid; and
- drain means in said drum below said rim for draining the fluid and resuspended particles from said drum during the purge cycle.

8. The apparatus of claim 7 including louver means mounted inside said top wall member and over said openings, said louver means having louver openings aimed in the direction of fluid rotation, said louver means thereby blocking passage of fluid and resuspended particles through the openings during the purge cycle while permitting flow through said louver openings during normal operation.

9. A self-purging centrifuge for clarifying contaminated fluid, comprising:

- housing;

a. housing;

- b. a drum rotatably mounted within the housing, the drum having top and side walls, the top wall containing ports for the discharge of clarified fluid, the drum containing a bottom opening for draining purged fluid;
- c. a rotor assembly rotatably mounted in the drum for directing contaminated fluid toward the side wall of the drum, said drum side wall collecting a layer of solid particles being centrifuged from the fluid, the rotor assembly including vanes, the outer edges of which extend outward beyond the discharge ports and are located a substantial distance from the side wall so as not to become embedded in the layer of particles, the outer portions of the vanes and the side wall of the drum generally defining a

5

10

15

- volume within which the contaminated fluid is centrifuged;
- d. means for driving the rotor assembly;
- e. means for introducing contaminated fluid into the rotor assembly;
- f. a rim mounted on the side wall of the drum at the lower end of the centrifuging volume, the rim extending inward beyond at least the outer edges of the discharge ports and providing a radial surface;
- g. means for collecting the clarified fluid;
- h. means for braking one of the drum and rotor assembly; and
- i. louver means for deterring the discharge of fluid through the discharge ports when braking occurs.
